Primary Examiner — John Windmuller*Assistant Examiner* — John R Yeh(74) *Attorney, Agent, or Firm* — Daniel J. Iden(57) **CLAIM**

The ornamental design for a floor pad, as shown and described.

DESCRIPTION

FIG. 1 is an orthogonal view showing the new design for a floor pad.

FIG. 2 is a top view thereof;

FIG. 3 is a bottom view thereof; and,

FIG. 4 is a right side profile view thereof; the left side view, front side view and back side view thereof being the same. The broken lines in the figures represent portions of the floor pad that form no part of the claimed design.
